ANTIBIOTICS

Winston Kennay Anslow, Slough, and George Desmond Wilkin, Uxbridge, England, assignors to Glaxo Laboratories Limited, Greenford, Middlesex, England, a British company

No Drawing. Filed Jan. 10, 1957, Ser. No. 633,380

11 Claims. (Cl. 195—80)

This invention is concerned with improvements in or relating to antibiotics and is more particularly concerned with improved methods for the production of the antibiotic described in copending application No. 602,634, filed August 7, 1956, and now abandoned in favor of continuation-in-part application 767,343, filed October 15, 1958, and there designated "E. 129."

The antibiotic E. 129, as disclosed in said application has been obtained by the aerobic cultivation on or in a suitable nutrient medium of an organism discovered by us and identified as belonging to the genus *Streptomyces*. This organism, which was isolated from a soil sample collected near Jericho in Jordan, was originally designated as *Streptomyces E. 129*, but is now named *Streptomyces ostreogriseus*.

Cultures of the organism have been deposited with the National Collection of Industrial Bacteria (N.C.I.B.) at the Department of Scientific and Industrial Research, Teddington, England, under number N.C.I.B. 8792 and also in the culture collection of the Northern Regional Research Laboratories (N.R.R.L.) at Peoria, Illinois, United States of America, under number N.R.R.L. 2558.

We have now found that improved results, particularly improved titres, are obtained in the production of E. 129 by culturing an E. 129 producing organism, particularly *Streptomyces ostreogriseus* on or in a suitable medium, if the medium contains available iron in a concentration within the range of from 30—135 parts per million (p.p.m.) and desirably within the range of from 35—55 p.p.m. A concentration of iron above 135 p.p.m. begins to show substantially inhibiting effect on the organism.

As previously stated in the said copending application it is preferred to produce E. 129 by the submerged fermentation of an E. 129-producing organism in a nutrient medium containing a complex organic source of nitrogen such as oatmeal, soya bean meal, corn steep liquor and the like, a carbohydrate and mineral salts. As is known organic materials such as the above mentioned sources of nitrogen often contain trace quantities of iron, and this should be allowed for in computing the quantity of iron to be added to the medium for the purpose of the present invention. It is the case however that many of the more important complex organic sources of nitrogen used in the culture of micro-organisms contain substantially the same amount of iron, i.e. from 10—20 p.p.m., so that an amount of additional iron of at least 25 p.p.m. and not more than 115 p.p.m. will usually be satisfactory. If an organic material with a greatly different iron content is used the amount of added iron must of course be correspondingly adjusted.

The nature of the source of the added iron does not appear to be important provided it is soluble in the fermentation medium and is substantially non-toxic to the organism and compatible with the resultant antibiotic; iron in both the ferrous and ferric states may be used. We have found that suitable sources of iron are ferric citrate, ferric chloride and ferrous ammonium sulphate.

2

It is known that limestone (chalk) chelates with iron. In certain of the media which we have used for the production of E. 129 we have used limestone as an ingredient together with iron and, in spite of the known chelating properties of limestone with iron, an increase in titre was obtained.

It has also been found that an improved titre in the production of E. 129 by fermentation is obtained when corn steep liquor is used in a medium also containing oatmeal and a source of carbohydrate. A particularly suitable quantity of corn steep liquor is 0.4—0.9% (by weight of solids) of the weight of the medium, preferably an amount of 0.7% by weight of solids. The preferred amounts of oatmeal are within the range 1—5%, advantageously 2.5%.

The ratio of corn steep liquor to soluble carbohydrates is also important in obtaining good titres. Thus—while in the absence of corn steep liquor no appreciable difference in titre is obtained using two media which contain, inter alia 0.5% and 1.5% by weight respectively of glucose—if corn steep liquor, say 0.7% by weight of solids, is added to each medium not only is an increase in titre of each obtained, but also an enhanced titre is obtained with the medium containing 1.5% glucose compared with that containing only 0.5% glucose. The effect of the corn steep liquor and source of carbohydrate would therefore appear to be synergistic.

In general we have found it preferable to have present 1.5% of soluble carbohydrate, especially glucose, when corn steep liquor is used.

A medium which we have found to be very suitable for use in the production of E. 129 is one containing oatmeal flour (preferably 2.5%), limestone (preferably 2.0%) and glucose (preferably 1.5%) adjusted to a pH of 6.8—7.0 with e.g. hydrochloric acid or NaOH and to which has been added corn steep liquor in an amount as set out above and preferably also containing added iron in an amount as set out above (preferably 30 p.p.m.).

In order that the invention may be well understood the following examples will now be given by way of illustration only, the parts being by weight.

A. EXAMPLES SHOWING THE EFFECT OF IRON

Example 1

Two sets of four 5-litre fermenters were prepared containing the basal oatmeal medium with 1.5% glucose and with 0.7% corn steep liquor, i.e.

	Percent
Oatmeal flour	2.5
Limestone	2.0
Corn steep solids	0.7
Glucose (sterilized separately)	1.5
(pH adjusted to pH 6.8—7.0 with sodium hydroxide).	

To one set of fermenters was added 60 parts per million of iron as ferric citrate. Each fermenter was inoculated with 2% of a vegetative culture of *Streptomyces E. 129* (grown on the above oatmeal medium without the addition of corn steep liquor and containing only 0.5% glucose) and fermented at 27° C. with an air flow of 3 litres per minute. Assays against *Sarcina lutea* gave the following results in u./ml.:

	Hours	Controls (no iron)	Plus 60 p.p.m. Fe
20		315	495
28		385	510
36		355	395

3
Example 2

The effect of iron was further explored using the same medium and conditions as in Example 1 but with levels of 30, 60 and 120 parts per million of iron in the form of ferric citrate. The average titres (three fermenters in each set) were as follows:

Hours	Controls (no iron)	Plus 30 p.p.m. Fe	Plus 60 p.p.m. Fe	Plus 120 p.p.m. Fe
20	410	465	445	500
28	480	620	525	455
36	415	465	375	345

Example 3

Example 2 was repeated using lower levels of iron, viz. 15, 30 and 45 parts per million, with the following results (averages of three fermenters):

Hours	Controls (no iron)	Plus 15 p.p.m. Fe	Plus 30 p.p.m. Fe	Plus 45 p.p.m. Fe
20	155	130	110	120
28	400	360	410	405
36	375	545	495	485

Example 4

To ensure that different sources of iron were equally beneficial three sets of four fermenters were prepared as in the Examples 1-3 but all with the addition of 30 parts per million of iron, one set using ferric citrate as before, another set using ferric chloride and the third set using ferrous ammonium sulphate. The following results were obtained, the figures being the average of each set:

Hours	30 p.p.m. iron as ferric citrate	30 p.p.m. iron as ferric chloride	30 p.p.m. iron as ferrous ammonium sulphate
28	520	490	510
36	445	485	475

It is clear that any of these salts can be used.

B. EXAMPLES SHOWING THE EFFECT OF CORN STEEP LIQUOR

Example 5

Three 5-litre fermenters were batched with three litre quantities of the following medium, the glucose portion being sterilised separately:

	Percent
Oatmeal	2.5
Limestone	2.0
Glucose	0.5

In addition, one fermenter contained 0.23% corn steep liquor solids, the second 0.46%, and the third 0.70%. The pH of each fermenter was adjusted to pH 6.8-7.0 with sodium hydroxide.

Each fermenter was fermented at 27-28° C. and the following results were obtained:

Hours	Corn steep liquor solids		
	0.23%	0.46%	0.70%
20	195	350	375
28	210	390	450

It will be seen that the lowest level of corn steep liquor gave no increase over the usual titre of 200-300 u./ml. which experience has shown to be obtainable on the basal medium, whereas 0.46% and 0.70% corn steep liquor gave substantial increases.

Example 6

To determine the best level of corn steep liquor four sets of three 5-litre fermenters were prepared, containing the basal oatmeal medium with 1.5% glucose. To one set was added 0.45% corn steep solids, to the second 0.7%, to the third 0.9% and to the fourth 1.1%. The fermenters were inoculated and fermented as before. The results are given in the table below, each figure being the average of three fermenters:

Hours	Corn steep liquor solids			
	0.45%	0.70%	0.90%	1.1%
18	486	400	400	165
26	375	410	375	245
36	420	410	415	180

It is evident that 1.1% corn steep solids has a deleterious effect on titre and that 0.9% is a reasonable top limit.

C. EXAMPLE SHOWING THE EFFECT OF GLUCOSE

Example 7

The effect of additional glucose was next determined. 5-litre fermenters containing the basal oatmeal medium with glucose at 0.5% and 1.5% levels and fermenters containing the basal oatmeal medium plus 0.7% corn steep solids with glucose at 0.5% and 1.5% levels were prepared, inoculated and fermented as in Example 5, with the following results in u./ml.:

Hours	Oatmeal Medium				Oatmeal Medium + 0.7% Corn Steep Liquor solids					
	Glucose, 0.5%		Glucose, 1.5%		Glucose, 0.5%		Glucose, 1.5%			
	(a)	(b)	(a)	(b)	(a)	(b)	(c)	(a)	(b)	(c)
20	198	304	214	125	374	486	326	368	346	374
28	192	300	210	132	512	456	428	564	448	515

It will be seen that the use of 1.5% glucose in the basal oatmeal medium has no beneficial effect over 0.5%, whereas a substantial increase in titre is obtained by the use of 1.5% glucose when 0.7% corn steep liquor solids are included.

We claim:

1. A process for the production of an antibiotic-containing medium of improved titre which comprises culturing *Streptomyces ostreogriseus* N.R.R.L. No. 2558 under submerged aerobic conditions in a liquid culture medium containing from 30-135 parts per million of available iron.
2. A process as claimed in claim 1 in which said medium contains from 35-55 parts per million of available iron.
3. A process for the production of an antibiotic-containing medium of improved titre which comprises culturing *Streptomyces ostreogriseus* N.R.R.L. No. 2558 under submerged aerobic conditions in a liquid culture medium containing a complex organic source of nitrogen, a carbohydrate and nutrient mineral salts and added assimilable iron in an amount of from 25-115 parts per million of said medium.
4. A process as claimed in claim 3 in which said medium contains as an added source of iron at least one iron salt selected from the group consisting of ferric citrate, ferric chloride and ferrous ammonium sulphate.
5. A process as claimed in claim 3 in which said medium comprises as a source of nitrogen, oatmeal and corn steep liquor.
6. A process as claimed in claim 3 in which said medium comprises glucose as carbohydrate.

7. A process for the production of an antibiotic-containing medium of improved titre which comprises culturing *Streptomyces ostreogriseus* N.R.R.L. No. 2558 under submerged aerobic conditions in a liquid culture medium containing a source of carbohydrate and a source of nitrogen comprising from 0.4 to 0.9% by weight of corn steep liquor solids and from 1 to 5% by weight of oatmeal.

8. The process as claimed in claim 7 in which said medium contains from 0.5-1.5% by weight of carbohydrate.

9. The process as claimed in claim 7 in which said culture medium also contains added assimilable iron in the amount of from 25-115 p.p.m. of said medium.

10. A process for the production of an antibiotic-containing medium of improved titre which comprises culturing *Streptomyces ostreogriseus* N.R.R.L. No. 2558 under submerged aerobic conditions in a liquid culture medium containing about 2.5% by weight of oatmeal flour, about 0.7% by weight of corn steep liquor solids, about 2.0% by weight of limestone, and about 1.5% by weight of glucose.

11. The process as claimed in claim 10 in which said culture medium contains about 30 p.p.m. of added assimilable iron.
